UNITED STATES PATENT OFFICE

115,370

DESIGN FOR A BATHING SUIT

Edward Mandel, Cleveland, Ohio

Application April 4, 1939, Serial No. 84,044

Term of patent 3½ years

To all whom it may concern:

Be it known that I, Edward Mandel, a citizen of the United States, residing at 2118 Abington Road, in the city of Cleveland, county of Cuyahoga, and State of Ohio, have invented a new, original, and ornamental Design for a Bathing Suit, of which the following is a specification, reference being had to the accompanying drawing, forming a part thereof:

I claim:

The ornamental design for a bathing suit, substantially as shown.

EDWARD MANDEL.
